Primary Examiner — Jack Reickel*Assistant Examiner* — John M Otte(74) *Attorney, Agent, or Firm* — FisherBroyles, LLP**CLAIM**

The ornamental design for a display screen with graphical user interface, as shown and described.

DESCRIPTION

FIG. 1 is a front view of a first image in a sequence for a display screen with graphical user interface showing the claimed design.

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof; and,

FIG. 7 is a front view of a seventh image thereof.

The appearance of the transitional image sequentially transitions between the images shown in FIGS. 1-7. The process or period in which one image transitions to another image forms no part of the claimed design.

The broken line showing of a display screen with graphical user interface is included for the purpose of showing portions of the article which form no part of the claim.
